PROPELLER

Starr K. Sherwood, Seattle, Wash.

Application June 4, 1935, Serial No. 24,931

4 Claims. (Cl. 170—165)

This invention relates to improvements in ship propellers and has particular reference to that class of propellers termed "the no drag type".

The principal object of the invention is to produce a propeller which will have a higher efficiency than the ordinary propellers used on vessels. A further object is to produce a propeller which may be applied to any ordinary vessel without materially altering its construction.

10 A further object is to produce a propeller mechanism wherein two propellers are employed so that the current set up by the first propeller is acted upon by the second propeller, thus giving double efficiency.

15 Other objects and advantages will be apparent during the course of the following description.

In the accompanying drawing forming a part of this specification and in which like numerals are employed to designate like parts throughout the same,

20 Fig. 1 is a fragmentary side elevation of a vessel having my invention applied thereto,

Fig. 2 is an end elevation of a propeller constructed in accordance with my invention,

25 Fig. 3 is an enlarged detail cross sectional view of the propeller shaft and the propellers mounted thereon, and

Fig. 4 is an enlarged cross sectional view on the line 4—4 of Fig. 2.

30 A ship is ordinarily propelled by a propeller shaft which is driven and upon this propeller shaft is mounted a propeller which rotates in the water, thus propelling the ship. It is my intention to employ two propellers rotating or revolving in opposite directions and to lead a jet of water to a point adjacent the leading edge of one of the propellers, the purpose of which will be later seen.

35 In the accompanying drawing wherein for the purpose of illustration is shown a preferred embodiment of my invention, the numeral 5 designates a ship having a propeller shaft 6 which is driven in the customary manner. To this shaft I attach a gear 7 which rotates therewith. This gear, in turn, meshes with spur gears 8 and 9 mounted upon shafts 11 and 12, which gears mesh with a gear 13 secured to a propeller hub 14 having propeller blades 16. All of these gears are enclosed in a housing 15. A propeller hub 17 is attached to the shaft 6 and has blades 18. The propeller blades 18 each have a duct 19 formed therein, which in turn communicate with openings 21 formed in the face of the propeller. A pipe 22 connects to a fitting 23 which in turn joins the end of the shaft 6 which is hollowed as

shown at 24 and communicates with the ducts 19. This pipe 22 connects with any suitable source of fluid supply such as the pump 24 (see Fig. 1).

The result of this construction is that when the vessel is under way the propeller blades 18 and 5 16 rotate in reverse directions due to the gearing arrangement shown in Fig. 3. At the same time water pumped through the pipe 22 enters the hollow portion of the shaft 6 and passes into the ducts 19 and out of the holes 21. It is a well 10 known fact that a propeller in revolving in the water is inefficient to a very large extent due to a suction or vacuum formed at the trailing edge of the propeller. It is, therefore, applicant's intention to force jets of water along the face of 15 the propeller in such a direction as to overcome this vacuum, thus giving the propeller a very much greater efficiency which is readily accomplished by the use of these jets.

While I have specified and illustrated the use 20 of propeller blades of ships, which blades set forth my improved construction, nevertheless, it is to be understood that with certain minor changes applied to the propellers of airplanes greater efficiency in airplanes can, likewise, be 25 realized.

It is to be understood that the form of my invention herewith shown and described is to be taken as a preferred example of the same and that various changes relative to the material, size, shape and arrangement of parts may be resorted to without departing from the spirit of the invention or the scope of the subjoined claims.

Having thus described my invention, I claim:—

1. In duplex ship propellers of the class described, the combination with a propeller shaft, of differential gear means mounted on said shaft and capable of driving said propellers in opposite directions, the blades of one of said propellers having ducts formed in opposite edges thereof, 30 and means for forcing fluid under pressure through said shaft and through the ducts formed in the blades of one of the said propellers.

2. In duplex ship propellers of the class described, the combination with a hollow propeller shaft, of gear means mounted on said shaft and capable of driving said propellers in opposite directions, the blades of one of said propellers having ducts formed in opposite edges thereof, and means for pumping fluid under pressure through 40 said hollow shaft and out through the ducts formed in said propeller blades.

3. In a device of the class described, the combination with a hollow propeller shaft, duplex propellers carried by said shaft, differential gear 45

50

55

means associated with said propellers to cause their opposite rotation, one of said propellers having ducts formed in its side edges and capable of ejecting jets of fluid therefrom, and means associated with said hollow shaft for forcing fluid under pressure from said ducts adapted to cause the vacuum to be broken forwardly of the said blades.

4. In a device of the class described, duplex propellers, one of which has ducts formed in its edges, said ducts extending from the axis of rotation to the edges of the blades of the propeller, and means for forcing fluid pressure through said ducts. 5

STARR K. SHERWOOD.
